UNITED STATES PATENT OFFICE.

HORACE P. BROWN, OF OAKLAND, CALIFORNIA, ASSIGNOR TO PACIFIC-BURT COMPANY, LIMITED, OF TORONTO, CANADA, A CORPORATION OF THE PROVINCE OF ONTARIO, CANADA.

MANIFOLDING SALES-BOOK.

1,202,789.

Specification of Letters Patent. Patented Oct. 31, 1916.

Application filed July 20, 1915. Serial No. 40,835.

To all whom it may concern:

Be it known that I, HORACE P. BROWN, a citizen of the United States, residing at Oakland, in the county of Alameda and 5 State of California, have invented certain new and useful Improvements in Manifolding Sales-Books, of which the following is a full, clear, and exact description, such as will enable others skilled in the art to 10 which it appertains to make and use the same.

My present invention relates to salesbooks, and has particular reference to covers properly designed for so-called "continuous" 15 books, in which a sheet is folded zigzag into sets of originals and duplicates between which a carbon is to be disposed when in use. The invention is not limited, however, to this form of book, as it may well be applied to others, as will be apparent after 20 the description is read.

The principal drawback to the use of the continuous book has been the difficulty of providing a satisfactory cover. In general these 25 covers have spring clips or clamps both at the top and at the bottom, the clip at one end of the book being arranged to hold a carbon sheet; in actual operation the carbon sheet often tears out on account of its sticky 30 nature, making it adhere to the slips as they are torn away, and the clip or clamp does not always hold it securely. In addition, if the clerk drops the book and it happens to strike in a particular way, one or both of 35 the clamps will release, and it will spring out, so that it has to be carefully reassembled; while the loading of the cover with a new pad or book is difficult because the two 40 spring clamps have to be manipulated at the same time.

To obviate the troubles which I have just described, I have provided the new form of cover herein illustrated and described. In my invention, after the sheet forming the 45 pad is folded, I punch two perforations, preferably adjacent to one end of the folded pad, and upon the cover or back I provide two posts which fit in the perforations. A clamp or spring clip of common form is also 50 provided adjacent to the posts. The book or cover is loaded by lifting the clamp, passing the perforated pad of sheets over the posts, and releasing the clamp. To provide for the difficulties pertaining to the use of

the ordinary carbon paper with clamps of 55 this character, I tack the carbon paper to a sheet of strawboard of proper size, and place it under the pad before the latter is put in position; the sheet of strawboard or pasteboard is perforated to fit over the posts. 60

The accompanying drawings show an embodiment of the invention just described.

In them Figure 1 is a perspective of the completed salesbook with part of the cover cut away, and Fig. 2 is a side elevation with 65 part of the spring clamp removed.

In the drawings, A is the back of the book, provided with a flange A¹ at one end thereof.

B is the cover, and C is the usual flexible 70 hinge, in the present case provided with a pencil holder C¹, which may or may not be employed as desired.

D is the clamp, which is a spring clamp of common form well-known in this connection. 75

E E are the posts to which I have referred. In the book from which the drawings were made, there are two of these posts, and they are shown rounded at the top. 80 They may be secured to the back in any desired manner, and there may be any required number of them according to the use to which the book is to be put. In very wide books, more than two may be desirable, and 85 in very narrow books one might be sufficient.

H shows the upper leaf of the zigzag continuous book, but as I have already explained pads of leaves of other forms may 90 be used, since the invention is equally applicable to them.

G is the carbon sheet, which is attached to a backing sheet F of pasteboard or strawboard, being stitched at f. Any suitable 95 form of attachment may be used. It will be understood of course that the sheet F is perforated to correspond with the posts E E so that the book may be easily assembled. Obviously the posts may be disposed in any 100 convenient position upon the back.

The device is assembled by lifting the clamp D, placing the carbon backing sheet F over the posts, inserting the folded pad in place over the posts which are disposed in 105 its perforations, releasing the clamp which presses down the pad into position, after which the carbon sheet G is disposed be-

tween two of the leaves in a well-known manner. The sheets of the pad have the usual weakened lines at or about the folds therein, and when a transaction has been recorded the upper sheet H is grasped and lifted slightly and pulled out from under the clamp. This releases the duplicate sheet also and permits the succeeding original to be raised for allowing the carbon sheet to drop into position for the next transaction. The original and duplicate leaves are then torn off and the carbon restored to its position.

The manner of applying the invention to books of other character, such as well-known triplicates and pads having stubs, etc., will be readily apparent from the foregoing description.

Having described my invention, what I claim as new and desire to secure by Letters Patent is:

1. In a manifolding salesbook, in combination, a back, posts secured thereto, a pad having openings registering with said posts, a clamp secured to said back to engage said pad between said posts and the adjacent end of said pad, a carbon sheet, and a backing sheet therefor having openings registering with said posts and underlying said pad.

2. In a manifolding salesbook, in combination, a back, a flange at one end thereof, posts at the other end thereof, a pad having perforations registering with said posts, and a spring clamp disposed to act on said pad between said posts and the adjacent end of said pad for holding the latter in position.

3. In a manifolding salesbook, a back, a flange upon one end of the back, posts secured to the back near the end opposite the flange, a pad having perforations registering with the posts, a spring clamp holding the pad in place, the clamp located upon the back to act between the posts and the adjacent end of the pad, a carbon sheet, a backing sheet to which the carbon sheet is at-

tached, and perforations in the backing sheet registering with the posts.

4. In a manifolding salesbook, a back, a pad composed of a sheet folded zigzag, means for detachably positioning the pad with respect to the back comprising a post engaging the pad, such post permitting the removal of the leaves of the pad thereover as desired, and a spring clamp pressing the folded sheet toward the back between such post and one end of the pad.

5. In a manifolding salesbook, in combination, a back, pad-positioning means thereon comprising a post and a clamp, and a pad composed of leaves arranged zig-zag and perforated near one end, the perforations engaging said post, said clamp pressing said pad toward said back at a point permitting movement of leaves over the outer end of said post during said pressure of said clamp.

6. In a manifolding salesbook, in combination, a back, pad positioning means thereon comprising a post and a clamp, a pad composed of leaves arranged zig-zag and perforated near one end, the perforations engaging said post, said clamp pressing said pad toward said back at a point permitting movement of leaves over the outer end of said post during said pressure of said clamp, a carbon sheet, and a backing sheet to which the carbon sheet is attached, the backing sheet having a perforation registering with said post.

7. In a salesbook, in combination, a back having spaced posts thereon, a pad to rest on said back and having spaced openings to receive said posts, and a yieldable clamp carried by said back and engaging said pad only at points removed from said openings.

In testimony whereof I affix my signature, in the presence of two witnesses.

HORACE P. BROWN.
